(57) **CLAIM**

The ornamental design for a combined universal serial bus adapter and base, as shown and described.

DESCRIPTION

FIG. 1 is a front view of the combined universal serial bus adapter and base, with the moveable antenna pointing upward;

FIG. 2 is a back view of the combined universal serial bus adapter and base, with the moveable antenna pointing upward;

FIG. 3 is a side view of the combined universal serial bus adapter and base (showing the antenna side), with the moveable antenna pointing upward;

FIG. 4 is a side view of the combined universal serial bus adapter and base (showing the side opposite the antenna), with the moveable antenna pointing upward;

FIG. 5 is a top view of the combined universal serial bus adapter and base; and,

FIG. 6 is a bottom view of the combined universal serial bus adapter and base.

The broken line drawing of a cord in FIGS. 3-5 is for illustrative purposes only and forms no part of the claimed design.
